EAR RADIO

John R. Norris, Phoenix, Ariz.

Application May 13, 1954, Serial No. 30,488

Term of patent 14 years

(Cl. D56—4)

Fig. 1

Fig. 4

Fig. 2

Fig. 3

To all whom it may concern:

Be it known that I, John R. Norris, have invented a new, original, and ornamental Design for an Ear Radio, of which the following is a specification, reference being had to the accompany drawing, forming a part thereof.

Fig. 1 is a perspective view of an ear radio having the features of my design.

Fig. 2 is an outside plan view of the device shown in Fig. 1.

Fig. 3 is an end elevation of the device shown in Figs. 1 and 2.

Fig. 4 is a section on the line 4—4 of Fig. 2.

I claim:

The ornamental design for an ear radio, as shown.
